INVENTOR.

UNITED STATES PATENT OFFICE

2,349,930

AIRCRAFT CARRIER

William H. Atkinson, San Francisco, Calif.

Application August 1, 1942, Serial No. 453,168

5 Claims. (Cl. 114—43.5)

The present invention relates to an improvement in combat ships of the so-called aeroplane carrier type, and more particularly to an arrangement embodying a plurality of superimposed decks over which aeroplanes may be moved in a continuous manner, together with a novel means for transferring aeroplanes from one deck to another, whereby the aeroplanes may make landings, be refueled and reloaded, and take-off in a continuous manner.

An object of the invention is to provide a novel construction for an aeroplane carrier from which a fleet of aeroplanes can operate in a continuous manner without interference with each other.

Another object of the invention is to provide a novel type of aeroplane carrier having a flight deck and a servicing deck, together with means that will form additional flight deck space and at the same time provide a practical and efficient manner for transferring the aeroplanes from one deck to the other.

A further object of the invention is to provide an arrangement for aeroplane carriers in which there is a flight deck, a refueling and re-loading deck, and a repair deck, together with means which will permit continuous refueling and reloading of a fleet of aeroplanes and which will facilitate the withdrawal of an aeroplane from flight for repair without interfering with the continuous operation of the remaining aeroplanes.

Another object of the invention is to provide a novel form of protection for combat and other ships which may be placed into operation after the ship has reached the combat zone and which may be moved into an inoperative position so as to not interfere with the speed of the ship in its approach to the battle zone.

Another object of the invention is to provide a novel form of submarine torpedo net by means of which an attacking torpedo may be ensnared and directed into an ineffective path of travel.

Other objects and advantages of the invention will be in part evident to those skilled in the art and in part pointed out hereinafter in the description taken in connection with the accompanying drawing, wherein there is shown by way of illustration and not of limitation preferred embodiments of the invention.

In the drawing:

Figure 1 is a side elevation of a converted freighter constructed in accordance with a preferred embodiment of the invention.

Figure 2 is a plan view of the ship illustrated in Figure 1 of the drawing.

Figure 3 is an end view in section showing the improved submarine torpedo protective means applied to the side of a ship of the type illustrated in Figure 1, and

Figures 4 and 5 are enlarged fragmentary views showing details of the protective means.

Due to the present emergency, there has been a sudden demand for auxiliary aeroplane carriers. To meet this demand the present program contemplates the conversion of conventional freighter-type ships now in construction into aeroplane carriers by omitting the usual super-structure and superimposing a flight deck over the hull from its bow to stern. It is believed that the present invention will find a wide application in this conversion program, particularly since it will provide for a substantial increase in the length of the flight deck without requiring any material alteration in the ship's hull and employs a simple and practical means for transferring the aeroplanes from one deck to another in an efficient manner.

Having reference to Figures 1 and 2 of the drawing, the numeral 10 designates a ship hull of conventional design. The hull 10 has an engine room 11 at the stern thereof, together with a control cabin 12 or super-structure which is positioned upon and extends out from one side of the hull 10. Extending over the hull 10 there is a main deck 14 that preferably will be unobstructed throughout its entire length and will be of rectangular outline. Immediately above the deck 14 and supported by stanchions 15 there is a flight deck 16 which is likewise of rectangular outline. Supported outwardly at the bow end of the ship by means of struts 17 there is a hinge-forming support 18 which carries a hingedly mounted inwardly extending flap or flight deck extension portion 19 that is adapted to hinge upon the support 18 so as to bring its inner end into register with either the main deck 14 or the flight deck 16. At the stern of the ship and supported upon struts 20 there is a similar hinge-forming support 21 upon which there is hingedly mounted a similar flight deck extension portion 22. These flight deck extending portions 19 and 22 respectively have integrally formed and depending arms 23 and 24 to which operating cables 25 and 26 are connected. These cables 25 and 26 are in turn controlled by power operated windlasses 27 and 28 which will serve to raise and lower the flight deck extending portions 19 and 22 between their respective limits of travel. The struts 17 and 20 may be of any suitable form and at their outer ends they are shown braced

by tie members 29 and 30 that are attached to and extend outwardly from each corner of the flight deck 16.

With this arrangement it will be seen that when the flight deck extending portion 19 is in its uppermost position and an aeroplane, designated by the numeral 31, is placed thereupon, as shown at the right of the drawing, the aeroplane may be lowered and rolled in and upon the main deck 14 where it can be serviced, refueled and reloaded with bombs. Then, after these operations, the aeroplane, designated by the numeral 32, can be positioned upon the flight deck extending portion 22, as shown at the left of the drawing, where it can be raised and placed into a position for immediate take-off from the flight deck 16.

To facilitate the withdrawal and repair of damaged aeroplanes in the event of return to the carrier, the main deck 14 is shown as having a hinged elevator section 33 which may be depressed and permit a removal of a damaged aeroplane from circulation to a lower or repair deck 34 without interfering with the free movement of other and undamaged aeroplanes over the main or servicing deck 14 and back to the flight deck 16.

Since the invention is illustrated as applied to the hull of a ship of the converted freighter type, for simplicity no armaments have been shown. But, it will be understood that, if desired, the hull of the ship may be provided with any number of bastions or blisters for the mounting of large calibre rifles or anti-aircraft guns.

Reference is now made to Figure 3 of the drawing where there is illustrated a further novel feature in the form of means for protecting the carrier, or any other type of ship, against attack from submarine torpedoes, particularly when the carrier is stationed at some rendezvous and is more or less stationary and, therefore, vulnerable. This improvement contemplates the provision of an outrigging in the form of struts 35 spaced throughout the length of the ship and over the ends of which suitable cables 36 are adapted to pass from suitable windlasses 37 to yoke-like members 38 that normally support two nets 39 and 40 in spaced parallel relation with each other and in a submerged position along the sides of the hull 10. When the ship or carrier is in motion, as in going from one point to another, the nets 39 and 40 may be raised out of the water, as shown by dot and dash lines in the drawing, where they will not form a hindrance to the progress of the ship.

As is more clearly illustrated in Figures 4 and 5 of the drawing, the cables 36 pass through or over the ends of the struts 35 and are secured to the balanced yokes or spreader arms 38 so that when tension is exerted upon the net 40, the spreader arm 38 will rock inwardly and upwardly and thus permit the net 39 to move downwardly. A novel feature of the nets 39 and 40 is that the net 39 has a mesh that will permit a relatively free passage of a torpedo 41 therethrough, and the mesh of the net 40 is of such dimension that it will not permit the free passage of a torpedo therethrough, but will ensnare the forward end of the torpedo and thus, in conjunction with the net 39 operating as above, cause the torpedo 41 to be turned upwardly out of its normal horizontal path, where the propulsion energy of the torpedo will be expended against its weight until this propulsion force has been entirely dissipated. Then, under normal circumstances, it is contemplated that the torpedo 41 will settle back, become dis-

engaged from the nets 39 and 40, and sink without doing any damage.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In an aircraft carrier of the type from which a plurality of aeroplanes are adapted to operate, the combination of a hull having the conventional propulsion and steering machinery, an unobstructed deck extending substantially over the length and breadth of said hull, a second or flight deck supported above said first deck, means extending outwardly from the end of said hull and having a support spaced outwardly in line with the end of said flight deck, and a deck forming portion of sufficient size to accommodate an aeroplane hinged upon said support and adapted to swing upwardly and downwardly about its hinged connection upon said support to bring its free edge into register with either of said decks and thereby facilitate the transfer of an aeroplane when placed thereupon from one to the other of said decks.

2. In an aircraft carrier of the type from which a plurality of aeroplanes are adapted to operate, the combination of a floating hull, a substantially unobstructed deck extending over the length and breadth of said hull, a second or flight deck supported above said first deck, means extending outwardly and upwardly from said hull and having a support spaced outwardly and on the level of said flight deck, and a deck forming portion of sufficient size to accommodate an aeroplane hinged upon said support adapted to move upwardly and downwardly about its hinged connection upon said support to bring its free edge into register with either of said decks and thereby facilitate the transfer of an aeroplane when placed thereupon from one to the other of said decks.

3. In an aircraft carrier of the type from which a plurality of aeroplanes can operate, the combination of a hull having the conventional propulsion and steering machinery, an unobstructed servicing deck extending substantially over the length and breadth of said hull, a second or flight deck supported above said servicing deck, an outwardly disposed deck forming portion at the bow and stern of said flight deck of sufficient size to accommodate an aeroplane, and support forming means extending outwardly from said hull upon which said outwardly disposed deck forming portions are hinged at their outer ends so that they may swing downwardly and upwardly about said support forming means to bring their inner ends into register with said servicing deck or said flight deck, whereby an aeroplane after landing may be transferred from the bow of said flight deck to said servicing deck and placed in a position for take-off at the stern of said flight deck without being returned over the flight deck.

4. In an aircraft carrier of the type from which a plurality of aeroplanes operate, the combination of a hull having the conventional propulsion and steering machinery, a servicing deck extending

substantially over the length and breadth of said hull, a flight deck supported at its sides above said servicing deck, an outwardly disposed deck forming portion at the bow and stern of said flight deck of sufficient size to accommodate an aeroplane, support forming means at the ends of said hull to which said outwardly disposed deck forming portions are hingedly connected, and means for swinging said outwardly disposed deck forming portions about their hinged connection with said support forming means, whereby they may be moved downwardly and upwardly about said support forming means to bring their free ends into register with said servicing deck or said flight deck.

5. In an aircraft carrier of the type from which a plurality of aeroplanes operate, the combination of a hull having the conventional propulsion and steering machinery, a servicing deck extending substantially over the length and breadth of said hull, a flight deck supported at its sides above said servicing deck, an outwardly disposed deck form-

10 ing portion at the bow and stern of said flight deck of sufficient size to accommodate an aeroplane, support forming means at the ends of said hull to which said outwardly disposed deck forming portions are hingedly connected, means for swinging said outwardly disposed deck forming portions about their hinged connection with said support forming means, whereby they may be moved downwardly and upwardly about said support forming means to bring their free ends into register with said servicing deck or said flight deck, a shop or repair deck below said servicing deck, and an elevator means including a portion of said servicing deck of sufficient size to accommodate an aeroplane, said portion of said servicing deck when lowered permitting transfer of an aeroplane from said servicing deck to said repair deck and when elevated completing said servicing deck and permitting movement of undamaged aeroplanes thereover from the bow and back to the stern of said flight deck after servicing.

15 20 WILLIAM H. ATKINSON.
